EXTRACTOR

Thomas Armstrong Baker, St. Louis, Mo.

Application August 24, 1936, Serial No. 97,512

2 Claims. (Cl. 210—71)

This invention relates to a new and improved extractor adapted to be combined with a washing machine or other device.

An object of this invention is to provide an extractor which may be positioned above a vat or washing chamber and yet allow access to the vat or chamber without necessitating the removal of the extractor.

Another object of this invention is to provide an extractor which utilizes an improved type of supporting and driving means.

Further objects and advantages will become apparent from the following description and accompanying drawings in which:

Fig. 1 is a cross-sectional view of the invention as applied to an agitator type of washing machine;

Fig. 2 is a top plan view of the machine shown in Fig. 1;

Fig. 3 is a section on line 3—3 of Fig. 1;

Fig. 4 is an enlarged sectional view of one type of extractor supporting means which may be used in my invention;

Fig. 5 is an enlarged sectional view of another type of extractor supporting means which may be used in my invention;

Fig. 6 is an enlarged sectional view of a type of stop valve which may be employed in my invention;

Fig. 7 is a sectional view on line 7—7 of Fig. 2;

Fig. 8 is a sectional view on line 8—8 of Fig. 2;

Fig. 9 is a sectional view on line 9—9 of Fig. 2;

Fig. 10 is a sectional view on line 10—10 of Fig. 2;

Fig. 11 is a sectional view on line 11—11 of Fig. 2;

Fig. 12 is a sectional view on line 12—12 of Fig. 2;

Fig. 13 is a sectional view on line 13—13 of Fig. 1; and

Fig. 14 is a sectional view on line 14—14 of Fig. 1.

Referring now to the drawings, the numeral 1 indicates a washing chamber provided with an agitator or paddle 3 and provided with a side wall 5. A drying chamber 7 may be secured to the washing chamber walls as by rivets 9. A centrifuge 11 with a large or substantial opening 13 therethrough which may be said to be of an annular trough shape may be rotatably supported within the drying chamber as by a track 15 and bearings 17. It may be desirable and advantageous to construct the track of a resilient material such as rubber which may have a hardened portion 19 formed integral with a soft portion 21.

This particular construction is optional as the track might be constructed wholly of a single type of suitable material and operate satisfactorily. Two methods of supporting the centrifuge are shown. One in Fig. 4 where the track is secured to the trough shaped centrifuge as by bolts 23 and may be rotatably supported in the bearings 17 which may be secured to the outer wall 25 of the drying chamber as by bolts 27. In another construction shown in Fig. 5 the track may be secured by flanges 29 on the drying chamber and bolts 31. In this latter type of construction the bearings 17 may be secured to the centrifuge as shown with bolts 33. An oil drip plate 35 may be secured to the outer wall of the drying chamber by suitable means.

Holes 37 in the drying chamber may be provided to allow any lubricant which might collect in the oil drip plate to escape to the outside.

Various means may be employed to drive the centrifuge. In the drawings I have shown a V-belt 39 which may cooperate with a suitable groove 41 in the drying chamber to rotate it. The belt is driven by means yet to be described.

Various types of centrifuge may be used with this invention. With the type shown in the drawings, the outer wall 43 may be corrugated as shown in Fig. 14. Slots 45 may be provided, as shown, in the corrugations with the axis of the slots inclined in the direction of rotation of the centrifuge. If desired, holes may be used instead of slots. Thus when the centrifuge rotates in the direction shown by arrow A, the clothes or other contents will be pressed against the wall and held in place by the corrugations while the water or other fluid which is to be expelled from the clothes will pass out through the holes and into the drying chamber. If the direction of rotation of the centrifuge is reversed so that it rotates in the direction shown by arrow B, air will be drawn in through the holes to fluff or aerate the clothes. The inner wall 47 of the centrifuge may be formed with a slope which will allow the clothes to slide into proper position around the centrifuge. This sloped wall 47 furnishes a means to dynamically balance the load in the centrifuge. If desired, the inner wall may be provided with corrugations and openings therein adapted to force air into the centrifuge. The corrugations might also be useful in strengthening the centrifuge.

A fluid passage 49 may connect the drying chamber 7 with the washing chamber. A valve 48 may be positioned in the fluid passage and may consist of valve seats 51, a tapered valve 53 secured to a rod or stem 55. A cap 59 encloses the

valve and seat. The valve stem may be provided with a handle or knob 61 and two indentations or recesses 63. A plunger 65 pressed by a spring 67 cooperates with the recess to maintain the valve in either opened or closed position.

The V-belt 39 may be driven from a suitable pulley 69 secured to a shaft 71 which may be supported in bearings 73. Two annular gears 75 are secured as shown to the shaft and are driven from a gear 77 which is driven from the gear mechanism 79 of a type which is usually employed with the type of washer shown. A forked bearing member 81 controls the vertical position of the gears 75 so that the direction of rotation of the shaft 71 may be changed by raising or lowering the forked bearing member 81. A rod 83 provided with suitable recesses 85, plunger 87 and spring 88 to cooperate therewith may be provided so that the gears may be positioned in either forward, neutral or reverse position. A splined arrangement may be used to rotatably secure the gears 75 or the pulley 69 to the shaft so that the pulley 69 may remain in fixed vertical position although the vertical position of the gears 75 may be changed. A handle 90 is provided to manually control the rotation of the shaft and hence the centrifuge. A lid 92 may be provided on the washer and may be arranged so that when it is raised the rotation of the centrifuge is stopped and it will be impossible to sustain any injury from the rapidly rotating member. The apparatus for this control is shown in Fig. 13 where a block 94 with a V-shaped opening 96 is slidably mounted in a support 98. A pin 100 is formed on the control rod 83. A lever 102 operates in connection with an extension 104 of the block 94. The lever 102 is secured to a shaft 106. The shaft 106 is secured to the lid 92 so that on opening the lid the shaft 106 rotates and moves the block 94 to force the pin 100 into the small end of the V-opening, thus moving the control rod to stop the centrifuge.

The lid or cover 92 is provided with openings 108 which allow air to be drawn in and through the clothes as previously outlined. An inner lid 110 is provided and will allow access to the washing or agitating chamber or vat without raising the large lid 92. Hinges 112 are provided for the lids. Louvres 114 are provided on the stationary portion 116 of the lid and provide means for the exit of air from the centrifuge.

A water outlet 117 may be arranged above the centrifuge and consists in a pipe 118 provided with holes 120 which cause the fluid in the pipe to be sprayed onto the contents of the centrifuge.

The pipe 118 is connected to a mixing faucet 121 through pipes 122. Pipes 124 and 126 are provided for a hose connection from hot and cold water supply lines.

A drain 128 from the drying chamber is provided with a valve 49 similar in construction with the valve 49 previously described. The members 61, 63, 65 and 67 may be similar to those members as previously described. Likewise the washing chamber is provided with a drain 130 and the corresponding valve fittings. An electric motor 132 may be used to drive the washing machine.

I have thus described my invention in connection with a washing machine; it might be equally advantageously employed for dyeing, bleaching, treating or other processes where a centrifuge is required.

In the machine which I have described, clothes may be placed in the washing chamber without removing the centrifuge and thoroughly cleansed after which they may be placed in the centrifuge 5 which may be first rotated in the direction to expel the water therefrom. The fluid passage from the drying to the washing chamber may be opened during this process to allow the soapy water removed from the clothes to be returned 10 to the washing chamber. The clothes may then be rinsed by opening the mixing faucet 120 and allowing water of the desired temperature to be sprayed onto the clothes in the centrifuge. If desired the clothes may be treated with steaming 15 water in this manner. The direction of rotation of the centrifuge may then be reversed and air drawn through the centrifuge to aerate or fluff them. After being centrifugally dried, the clothes may be removed from the dryer. Rinse water 20 may be allowed to pass from the drying chamber through the drying chamber drain. Since the opening in the centrifuge is large, the agitator may be removed through the opening without removal of the centrifuge. Likewise, clothes may be placed in and removed from the washing 25 chamber while the centrifuge is in operation.

Since the drying chamber is located above the washing chamber it is not necessary to employ a pump for pumping the water back into the washing chamber when desired. This arrangement also makes it possible to spray water over the clothes in the centrifuge and simultaneously drain such water out.

While I have illustrated and described but one 35 embodiment of my invention, it will be apparent to those skilled in the art that various omissions, additions, substitutions, changes and modifications may be made in the method and apparatus illustrated without departing from the spirit and 40 scope of the invention as set forth in the appended claims.

I claim as my invention:

1. In the drying chamber of a combined washing and drying machine, a reversible annular 45 trough-shaped centrifuge, a track secured to the outer periphery of the centrifuge, a drying chamber, a set of bearings secured to a wall of the drying chamber and cooperating with the under side of said track to rotatably support the centrifuge, another set of bearings secured to a wall of the 50 drying chamber and cooperating with the upper side of said track to prevent any vertical movement of the centrifuge and driving means to rotate the centrifuge.

2. In the drying chamber of a combined washing and drying machine, a reversible annular trough-shaped centrifuge, a track secured to the outer periphery of the centrifuge, said track being tapered outwardly therefrom, a drying chamber, 55 a set of bearings secured to a wall of the drying chamber and cooperating with the under side of said track to rotatably support the centrifuge, another set of bearings secured to a wall of the drying chamber and cooperating with the upper side of said track to prevent any vertical movement of the centrifuge, both sets of bearings 60 cooperating with the tapered track to define the path of rotation of the centrifuge and driving means to rotate the centrifuge.
